TWO-CYCLE SCAVENGING SYSTEM

Kurt Froehlich, Milwaukee, Wis., assignor to Nordberg Manufacturing Company, Milwaukee, Wis., a corporation of Wisconsin

Application July 25, 1956, Serial No. 600,094

10 Claims. (Cl. 123—65)

My invention is in the field of internal combustion engines and is a new and improved supercharging and/or scavenging system usable primarily on or with two-cycle engines.

A primary object of my invention is a new and improved two-cycle supercharging system for either diesel, dual-fuel or gas engines.

Another object is a scavenging system for two-cycle engines to lower the temperature of the cylinder charge.

Another object is a scavenging and supercharging system with an improved scavenging efficiency.

Another object is a scavenging system for two-cycle engines with a unique air movement during scavenging.

Another object is a scavenging and supercharging system for two-cycle engines which increases the effective stroke of the piston by lowering the exhaust and scavenging ports.

Another object is a scavenging and supercharging system for two-cycle engines which gives a better or more effective blow-down of the exhaust gases.

Another object is a scavenging system for two-cycle engines which reduces the cylinder mean temperature.

Other objects will appear from time to time in the ensuing specification and drawings in which:

Figure 1 is a vertical section through a two-cycle engine with my invention;

Figure 2 is a section along line 2—2 of Figure 1;

Figure 3 is a section along line 3—3 of Figure 1; and

Figures 4, 5 and 6 are similar to Figure 1, but on a reduced scale, showing the operation of the scavenging system.

In Figure 1 a cylinder 10 with the usual liner 12 has a suitable cylinder head 14 which may be held on by bolts 16 or otherwise. The cylinder head may be provided with suitable openings or channels for valves, fuel injectors and the like. For example, assuming that the engine is a dual-fuel engine, a fuel injector of any conventional type could be positioned at 18, a gas valve at 20, and possibly a starting air valve at 22, or suitable spark plug openings might be provided if the engine is a gas-fueled, spark-fired engine. Be this as it may, the details of the auxiliary equipment, such as the fuel supply system for the cylinder head, are not important except to say that the invention is possibly most pertinent to a gas engine.

A piston 24, of any suitable construction is provided in the cylinder to compress the entrapped charge and expand through a working stroke when the cylinder contents are ignited by any suitable means.

The scavenging system for the cylinder includes two rows of ports, an upper or top row, indicated generally at 26, and a lower or bottom row, shown generally at 28.

The inlet side, designated generally at 30, may have a suitable inlet manifold, while the exhaust side, designated generally at 32, may have a suitable exhaust manifold. Neither is shown as they may be conventional.

2

Regardless of the types of manifolds or headers that are used, air at an elevated pressure, and possibly cooled, is supplied to the inlet side from a scavenging blower or a supercharger or both.

- 5 Considering the lower or bottom row of ports in Figure 3 first, a box or air chamber 34 extending completely around the cylinder liner opens on the inlet side 30 and is closed to the exhaust side so that all of the ports in the lower row are inlet or scavenging ports. 10 As shown in Figures 2 and 3, the cylinder and liner are somewhat symmetrical about the center line 36. The ports 38 on each side of the center line on the inlet side of the engine are disposed at an acute or somewhat steep angle to the cylinder axis so that the scavenging 15 air will have a substantial vertical component of movement when it enters the cylinder, while the ports 40 on opposite sides of the center line at the exhaust side of the engine are practically at right angles to the cylinder axis. The inclination and disposition of these ports is 20 probably best shown in Figure 1. Moving from the lateral ports 40 around to the steeply inclined ports 38, the inclination of the ports may progress uniformly around each side until the steepest inclination is reached at the port 38. It should be understood that corresponding ports symmetrically opposite each other may be 25 matched in inclination. At the same time, all of the ports may be directed towards a scavenging axis 42 which is parallel to but offset from the cylinder axis 44. 30 Turning to the upper row of ports, as shown in Figure 2, the inlet side is divided into two inlet passages or cavities 46 which are disposed symmetrically on each side of the center line 36, each being controlled by a check valve 48 to prevent reverse scavenging. The 35 ports in the upper row are divided between inlet and exhaust ports. As shown, the inlet ports may include the first three ports 50, 52 and 54 on each side of the center line, and the line of direction of each of these inlet ports, six in number, may also be directed at the 40 scavenging axis 42 and disposed at a suitable inclination, each possibly being parallel to the inclination of the scavenging ports below them. The exhaust ports may include the ports designated 45 56, 58, 60 and 62 arranged symmetrically on opposite sides of the center line 36 and separated from the inlet passage by a suitable wall structure 64 on each side. The inlet ports in the upper row are separated from the lower row inlet ports by suitable walls 66 and 68, shown in Figure 1, which are controlled by the check 50 valves. The upper edge of the inlet ports in the upper or top row may all be in the same lateral plane, designated generally at 70, which is slightly above the upper edge of the exhaust ports which may also be or fall in a common plane, designated generally at 72, the distance 55 being designated generally at 74, so that during the compression or upward stroke of the piston, the exhaust ports will be covered before the inlet ports are fully closed so that the cylinder will receive a supercharge. By the same token, the exhaust ports cover the majority 60 of the port area of the top row of ports so that the contents of the cylinder will blow down rapidly at the end of the piston's expansion stroke.

The volume of the inlet passages from the opening into the cylinder back to the check valve, designated at 65 76, is reduced to a minimum by moving the check valve in as far as possible so that when the piston uncovers these ports during its power stroke, as little exhaust gas as possible will blow into the upper inlet cavities before the pressure in the cylinder drops below the scavenging 70 and supercharging pressure.

In Figures 4, 5 and 6, the operation of the scavenging system has been shown. In Figure 4, the piston 24 is on

its expansion stroke and only the upper row of ports has been uncovered. The high pressure gases in the cylinder blow down through the exhaust ports, as indicated generally by the arrow at 78, and the scavenging air from the inlet ports in the upper row enters as at 80 at a substantial angle to the cylinder axis 82.

In Figure 5, the piston is at or near bottom dead center and the lower row of ports has been uncovered. The inlet or scavenging air from the ports 40 on the exhaust side but in the bottom row moves in a more or less lateral direction as indicated by the arrow 84. The air entering through the ports in the lower row on the scavenging or inlet side at 38 flows in at a substantial angle as at 86. The two currents collide in the neighborhood of the point 88 and the resulting mixture current is deflected upwardly into the top of the cylinder on the right side at 90. The air from the scavenging or inlet ports in the top row is deflected as indicated by the arrow 92 into the top right pocket 90 of the cylinder to clean out the residual hot gases which might otherwise remain. The cylinder head is domed or otherwise shaped as at 94 so that the gases flow across and clean out the left top pocket 96 before returning to the flat exhaust ports as at 98.

In Figure 6, the piston is shown on its compression stroke covering the lower row of ports and the cross current from the inlet ports on the exhaust side of the bottom row is cut off. The contents of the cylinder have been cleaned or flushed out and a fresh charge of air is being supplied through the inlet ports in the upper row as indicated generally at 100. This stream of air returns to the original direction, such as in Figure 4, and the excess and the remaining products of combustion will exhaust at 102.

It should be noted that the scavenging air from the inlet ports in the upper row initially enters at a substantial angle to the cylinder axis and is primarily directed more toward the center of the cylinder. When the piston uncovers the lower row of ports, a lateral current of air from the flat or perpendicular inlet ports on the exhaust side collides with the current from the upper inlet ports and forces the scavenging air into the right top pocket. During the compression stroke, the lower row of ports will be covered and the air current from the inlet ports in the upper row will resume its flow more toward the center of the cylinder. I think of the movement of the air from the inclined direction at 80 in Figure 4, to the almost vertical direction at 92 in Figure 5, back to the inclined direction at 100 in Figure 6, as a fan action which serves to sweep the hot pockets of exhaust gases from the top of the cylinder.

The use, operation and function of my invention are as follows:

My scavenging system for two-cycle engines consists generally in having two rows of ports around the cylinder wall, one above the other. Preferably the two rows of ports each extend completely around the cylinder. The lower row of ports is connected to the scavenging side and only scavenging air enters through these ports. The upper row of ports is divided between inlet and exhaust ports, the majority being exhaust ports, and the inlet ports in the upper row are used for both scavenging and supercharging. It is important that the upper row has more area for exhausting than for supercharging.

The scavenging pattern or air flow path is shown generally in Figure 1, and it can be seen that the fresh scavenging air enters from all sides of the cylinder through the lower row of ports but moves first laterally and then somewhat upwardly from the inlet ports 40 on the far side of the cylinder from the normal scavenging side. In effect, the scavenging air flows toward the scavenging axis 42 with a large lateral component of movement and then axially upward to the top of the cylinder before turning across the top and coming down the opposite side of the cylinder to the exhaust ports in the upper row.

It is important that the majority of the area in the upper row of ports be devoted to exhausting the products of combustion so that a quick blow-down can be achieved. I have found that by this arrangement the upper row of ports can be lowered somewhat while achieving the same blow-down in less piston movement, thereby acquiring a longer expansion stroke at the same time which results in more power output at the crank shaft.

It is additionally important that the check valves for the scavenging and supercharging ports in the upper row be moved in as close to the cylinder liner as possible so that the blow-back volume at 76 is reduced. This reduces the temperature of the cylinder charge and results in a substantial power increase.

Because the majority of the area of the ports in the upper row can be devoted to exhausting the products of combustion, the scavenging efficiency of my cylinder will be increased. This is caused by the quicker release of the exhaust gases. I find that making the exhaust areas approximately 55-60% of the total port area in the upper row will increase the scavenging efficiency a substantial amount.

The fan action of the scavenging air serves to sweep the top of the cylinder of hot spots. I have found that this air movement effectively cleans the right and left upper corners of the cylinder, if cylinders can be considered to have corners. In any event, the cross rush of air from the lateral inlet ports on the exhaust side serves to deflect the scavenging air into the opposite pockets 90 and 96, which might otherwise harbor hot spots of exhaust gas.

While I have shown and described a preferred form of my invention, it should be understood that numerous modifications and changes can be made, all within the scope of the invention. For example, the invention can be applied to two-cycle gas, diesel or dual-fuel engines. It can be used on scavenged engines alone or on supercharged engines, using relatively high inlet manifold pressures. I, therefore, wish that my invention be unrestricted except as by the appended claims.

I claim:

1. In a two-stroke cycle internal combustion engine, a cylinder and cylinder head, a piston in the cylinder, a plurality of annularly arranged scavenging inlet air ports in the cylinder, a second plurality of annularly arranged ports in the cylinder in a plane adjacent the first plurality but toward the cylinder head, a substantial number of the ports in a group on one side of the cylinder in the second plurality being exhaust ports with the remainder on the other side of the cylinder being scavenging inlet air ports, the scavenging inlet air ports in the first and second plurality and the exhaust ports in the second plurality being so directed relative to the axis of the cylinder and relative to each other such that the scavenging air will ascend on the other side of the cylinder axis adjacent the scavenging inlet air ports in the second plurality and will descend on the said one side of the cylinder adjacent the exhaust ports in the second plurality to exit through such exhaust ports.

2. The structure of claim 1 in which the scavenging inlet air ports in the second plurality rise slightly above the exhaust ports in the second plurality, and a scavenging check valve mechanism for the scavenging inlet air ports in the second plurality.

3. In a two-stroke cycle internal combustion engine, a cylinder, cylinder head and piston, and a scavenging system including inlet and exhaust sides on opposite sides of the cylinder, two rows of ports around the cylinder wall, one above the other, the majority of the ports in the top row being in direct communication with the exhaust side and functioning as exhaust ports, substantially all of the ports in the bottom row and the remainder of the ports in the top row being in direct communication with the inlet side and functioning as inlet ports, each port in the bottom row having a cor-

responding port generally above it in the top row, the inlet ports in the bottom row on the exhaust side being laterally disposed generally perpendicular to the cylinder axis, the inlet ports in the bottom row on the inlet side being substantially inclined at an angle to the cylinder axis, the intermediate inlet ports in the bottom row uniformly increasing in inclination to the cylinder axis symmetrically around each side from the generally perpendicular inlet ports on the exhaust side to the substantially inclined inlet ports on the inlet side, each inlet port in the top row being generally matched in inclination to the cylinder axis to the inclination of its corresponding inlet port below it in the bottom row, all of the exhaust ports in the top row being laterally disposed generally perpendicular to the cylinder axis.

4. The structure of claim 3 in which the inlet ports in the top row rise slightly above the exhaust ports so that, during the compression stroke, the inlet ports will be fully closed after the exhaust ports and the cylinder will have a supercharge of air.

5. The structure of claim 4 in which a scavenging check valve mechanism is provided for the inlet ports in the upper row only.

6. In a two-stroke cycle internal combustion engine, a cylinder, cylinder head and piston, and a scavenging system therefor including inlet and exhaust sides generally on opposite sides of the cylinder, two rows of ports around the cylinder wall, one above the other, the majority of the ports in the top row being in communication with the exhaust side and functioning as exhaust ports, substantially all of the ports in the bottom row and the remainder of the ports in the top row being in communication with the inlet side and functioning as inlet ports, each port in the bottom row having a corresponding port generally above it in the top row, the inlet ports in the bottom row on the exhaust side being laterally disposed generally at right angles to the cylinder axis, the inlet ports in both rows on the inlet side being substantially inclined to the cylinder axis, all of the exhaust ports in the top row being laterally disposed generally at right angles to the cylinder axis.

7. In a two-stroke cycle internal combustion engine, a cylinder, cylinder head and piston, and a scavenging system therefor including inlet and exhaust sides generally on opposite sides of the cylinder, two rows of ports around the cylinder wall, one above the other, the majority of the ports in the top row being in communication with the exhaust side and functioning as exhaust ports, substantially all of the ports in the bottom row and the remainder of the ports in the top row being in communication with the inlet side and functioning as inlet ports, the inlet ports in the bottom row on the exhaust side being laterally disposed generally at right angles to the cylinder axis, the inlet ports on the inlet side being substantially inclined to the cylinder axis, all of the exhaust ports in the top row being laterally disposed generally at right angles to the cylinder axis.

8. In a two stroke cycle internal combustion engine, a cylinder, cylinder head and piston, and a scavenging system therefor including inlet and exhaust sides generally on opposite sides of the cylinder, two rows of ports around the cylinder wall, one above the other, the majority of the ports in the top row being in communication with the exhaust side and functioning as exhaust ports, substantially all of the ports in the bottom row and the remainder of the ports in the top row being in communication with the inlet side and functioning as inlet ports, the inlet ports in the bottom row on the exhaust side being laterally disposed generally at right angles to the cylinder axis, the inlet ports on the inlet side being substantially inclined to the cylinder axis, all of the exhaust ports in the top row being laterally disposed generally at right angles to the cylinder axis.

as inlet ports, the inlet ports in the bottom row being constructed to direct a lateral and upward main air current offset in the cylinder adjacent the inlet side, the inlet ports in the top row rising slightly above the upper level of the exhaust port and being constructed to direct an initial upward air current in the cylinder adjacent the inlet side at a substantial angle to the cylinder axis during the piston's expansion stroke after it has uncovered the upper row of ports but before it uncovers the bottom row, all of the ports in both rows being constructed so that when both rows of ports are uncovered by the piston, the main air current from the inlet ports in the bottom row will merge with and tend to deflect the initial air current from the inlet ports in the top row into the top of the cylinder in a direction more generally parallel to the cylinder axis to fully scavenge the top of the cylinder and cylinder head.

9. In a two stroke cycle internal combustion engine, a cylinder, cylinder head and piston, and a scavenging system therefor including inlet and exhaust sides generally on opposite sides of the cylinder, two rows of ports around the cylinder wall, one above the other, the majority of the ports in the top row being in communication with the exhaust side and functioning as exhaust ports, substantially all of the ports in the bottom row and the remainder of the ports in the top row being in communication with the inlet side and functioning as inlet ports, each port in the bottom row having a corresponding port generally above it in the top row, the inlet ports on the inlet side being more inclined to the cylinder axis than the inlet ports on the exhaust side, all of the exhaust ports in the top row being laterally disposed generally at right angles to the cylinder axis.

10. In a two stroke cycle internal combustion engine, a cylinder, cylinder head and piston, and a scavenging system therefor including inlet and exhaust sides generally on opposite sides of the cylinder, two rows of ports around the cylinder wall, one above the other, the majority of the ports in the top row being in communication with the exhaust side and functioning as exhaust ports, substantially all of the ports in the bottom row and the remainder of the ports in the top row being in communication with the inlet side and functioning as inlet ports, the inlet ports in the bottom row being constructed to direct a lateral and upward main air current offset in the cylinder adjacent the inlet side, the inlet ports in the top row being constructed to direct an initial upward air current in the cylinder adjacent the inlet side at a substantial angle to the cylinder axis during the piston's expansion stroke after it has uncovered the upper row of ports but before it uncovers the bottom row, all of the ports in both rows being constructed so that when both rows of ports are uncovered by the piston, the main air current from the inlet ports in the bottom row will merge with and tend to deflect the initial air current from the inlet ports in the top row into the top of the cylinder in a direction more generally parallel to the cylinder axis to fully scavenge the top of the cylinder and cylinder head.
